ALFONS H. NEULAND, OF SAN FRANCISCO, CALIFORNIA.

MAGNETO.

1,138,726.

Specification of Letters Patent. Patented Nov. 30, 1915.

Application filed September 3, 1912. Serial No. 718,237.

To all whom it may concern:

Be it known that I, ALFONS H. NEULAND, a subject of the Czar of Russia, and a resident of the city and county of San Francisco and State of California, have invented certain new and useful improvements in Magnetos, of which the following is a specification.

The invention relates to magnetos which are used in connection with internal combustion engines to generate the electric current for producing the firing spark.

The object of the invention is to produce a magneto of substantially the same size as now in general use which is capable of producing the desired spark and current for illumination purposes.

Another object of the invention is to provide a magneto which may be operated independently of the engine to generate a current when the engine is at rest.

It is the present tendency in automobile practice to illuminate the lights on the car with electricity, and heretofore, it has been necessary to install a separate generator or battery for this purpose. It is also desirable to produce a spark in the engine cylinders while the engine is at rest, for the purpose of starting the engine, without cranking, and this has heretofore necessitated the use of a separate battery. These results are accomplished by the magneto of my invention, without making the magneto of greater size than is now the general practice.

The invention possesses other advantageous features, which, with the foregoing, will be set forth at length in the following description, where I shall outline in full that form of the invention selected for illustration in the accompanying drawings, in which:

Figure 1 is a vertical longitudinal section taken through the magneto. Fig. 2 is a transverse section taken on the line *a—a* Fig. 1. Fig. 3 is a partial sectional view taken on the line *b—b* Fig. 1. Fig. 4 is an end view of the distributor. Fig. 5 is a side view of the distributor.

The magneto consists of a suitable frame 2 in which is secured the permanent magnet 3. This magnet is formed of a plurality of laminated plates 4 securely held together and to the frame by the bolts 5. The plates 4 are preferably circular in form, as shown in Fig. 2 and are formed with arms or pole pieces 6 and 7 of opposite polarity. The

60 pole pieces are divided into two sections 6^a—6^b and 7^a—7^b by the groove or channel 8, but the two sections 6^a—6^b are of one polarity and the sections 7^a—7^b are of the opposite polarity. The inner faces of the pole pieces are provided with teeth 16^a—16^b—17^a—17^b arranged parallel to each other and extending in the direction of the length of the magnet. The teeth on each section are 65 equally spaced apart from each other, and the two adjacent teeth on the sections of one pole piece are spaced apart a distance equal to one-half the spacing of the teeth on each section. That is, the adjacent teeth 16^a—16^b or 17^a—17^b are spaced apart a distance equal to one-half the distance between the teeth 16^a or 16^b or 17^a or 17^b.

70 Mounted in the frame and rotatable between the pole pieces is a core 12 which is 75 formed of laminations securely held together. The core is provided with teeth 13 which are spaced apart the same as the teeth on the sections of the pole pieces. It is evident that as the core revolves, the teeth 80 thereon coincide alternately with the teeth on sections 16^a—17^a and 16^b—17^b, producing a flux first from 16^a to 17^a, and then from 16^b to 17^b. Since the core serves to shift the 85 passage of the magnetic flux alternately through the sections 6^a—7^a and 6^b—7^b, I shall hereinafter refer to it as a flux valve. It is 90 evident that a rotation of the flux valve through a distance equal to one-half the spacing of the teeth will cause a shifting of 95 the lines of force.

Arranged in the channels or grooves 8 is a coil or winding 14 in which the current is induced, due to the shifting of the lines of force passing therethrough. Since each reversal of the magnetism through the coil induces an electromotive impulse in the coil, it is evident that a large number of impulses are produced for each revolution of the flux valve, the number of impulses being twice 100 the number of teeth on the valve.

105 The magneto illustrated in the drawings is adapted to be used in connection with a four cylinder, four cycle engine, but it is evident that the distributor can be altered to conform to any design of engine. Since the duration of the spark used for igniting the explosive charge is of short duration, it is necessary to employ only a small number of the impulses generated in the coil for sparking purposes, allowing the greater number of such impulses to be used for other pur-

poses, such as the illumination of head-lights or the operation of electric horns and whistles.

The core or flux valve is mounted on the shaft 21 which is driven by the engine shaft 22 through the gears 23-24 which are of such size that the shaft 21 makes two revolutions for each revolution of the engine shaft. The gear 24 is fixed to the sleeve 25 which is mounted for independent rotation on the shaft 21. The sleeve 25 is provided on its outer end with a single tooth ratchet 26 which engages a similar ratchet on the sleeve 27, which is movable longitudinally of the shaft but is splined thereto, so that it rotates with the shaft. The sleeve 27 is held against the sleeve 25 by the spring 29 surrounding the shaft. As the engine shaft revolves, the flux valve is also revolved, through the agency of the clutch, but when the engine shaft is stationary, the flux valve shaft may be rotated in the proper direction by the crank or handle 30, thereby allowing a current to be produced when the engine is at rest. This rotation does not disturb the relation between the position of the distributor and the position of the pistons in the engine, so that when the engine starts the timing of the spark is correct.

Arranged between the handle 30 and the valve shaft is a clutch which becomes disengaged when the engine starts, thereby allowing the handle to remain at rest. The clutch consists of the toothed member 51 formed on the sleeve 52 loosely mounted on the valve shaft and to which sleeve the handle is attached. Arranged on the valve shaft is a similar toothed member 53. Bearing against the sleeve 52 is a spring 54 which operates to normally hold the toothed members apart. When it is desired to produce a spark with the engine at rest, the sleeve is pushed in, compressing the spring and bringing the two parts of the clutch into mesh and the handle is rotated. The clutch on the opposite end of the shaft allows the shaft to be rotated by disengaging it from the engine shaft.

Loosely mounted on the sleeve 25 is the fiber drum 31 of the distributor. This drum is rotated at the proper speed by the connected gears 32-33 mounted on the stub shaft 34. Gear 32 meshes with a gear 35 formed on the end of the sleeve 25, and gear 33 meshes with a gear 36 on the drum. Embedded in the circumferential face of the drum is a metal ring 37 having an offset tongue or section 38, which comes into contact alternately with the brushes 41-42-43-44, which are connected to the respective spark plugs of the four cylinder engine. Bearing against the continuous ring 37 is a brush 45 which is connected to the sparking circuit.

In order that the current may be directed

to the sparking circuit at the proper intervals and to the lighting circuit at other times, a contactor or switch operated by the rotating shaft is necessary. Arranged on the valve shaft is a disk 46 having a depression 47 formed in the circumferential face thereof. Mounted on the casing or cap 48 attached to the frame of the magneto is a spring held contactor arm 49 bearing a roller 55 engaging the face of the disk. It is evident that as the disk revolves, the roller moves into and out of the depression 47, causing a movement of the free end of the arm 49. Secured to the free end of the arm is a sleeve 56 in which are arranged at opposite ends, the contact points 57-58. Mounted on the casing 48 and insulated therefrom and from each other are terminals 61-62 of the sparking and lighting circuits respectively. These terminals are arranged adjacent the contact points 57-58 so that when the roller is riding over the face of the disk, the point 58 is in contact with terminal 61 closing the lighting circuit and opening the spark circuit, and when the roller enters the depression in the disk, the point 57 is in contact with terminal 61, closing the sparking circuit and opening the lighting circuit. In order that no sparking may occur at these contacts as the circuits are opened and closed, I so arrange the contact points so that the circuit to be made is established before the existing circuit is broken. This is accomplished by making the contact points 57-58 slidable within the sleeve 56 and holding them pressed apart by the spring 64. That point which is in circuit is pressed into the sleeve by the contacting terminal, to such an extent, that as the sleeve moves away from said terminal, the point does not reach the end of the sleeve and be separated from the terminal until the other terminal and contact point are in contact. Attached to the casing 48 at a suitable place is a rocker arm 65 to which is attached a lever or arm for rotating the casing when it is desired to advance or retard the spark. One end of the coil 14 is connected to the contactor arm 49 and the other end is connected with the lighting circuit and with the low tension side of the sparking circuit.

I claim:

1. In a magneto, the combination of a stationary permanent magnet provided with pole-pieces, each pole-piece being divided into two substantially equal parts by a longitudinal channel, a plurality of teeth on each pole-piece part, a rotatable toothed flux valve arranged between said pole-pieces and a single winding arranged in said channels and encircling the flux valve.
2. In a magneto, a permanent magnet comprising a body, pole-pieces connected to said body at opposite sides by relatively narrow necks, said pole-pieces being each di-

vided into two parts by a longitudinal channel and teeth on each pole-piece part.

3. In a magneto, a permanent magnet comprising a body, pole pieces connected thereto by relatively narrow necks, said pole-pieces being provided with longitudinal channels occurring adjacent said necks, said channels dividing each pole-piece into two pole-piece parts and teeth on the inner faces of said pole-piece parts.

4. In a magneto, the combination of a permanent magnet having toothed pole-pieces connected to the body of the magnet by relatively narrow necks, the pole-pieces being divided into two parts by channels formed adjacent said necks, the teeth on

each pole-piece part being of the same pitch and the pitch of the adjacent teeth of two adjacent pole-piece parts being equal to an odd multiple of one-half the pitch of the 20 teeth on the parts, a single winding arranged in said channels and a toothed flux valve arranged between the pole-pieces and within the winding.

In testimony whereof, I have hereunto set 25 my hand at San Francisco, California, this 28th day of August, 1912.

ALFONS H. NEULAND.
